France, a corporation of France

Application July 21, 1953, Serial No. 26,064

Term of patent 14 years

(Cl. D58—26)

To all whom it may concern:

Be it known that I, Louis Leon Dujoncquoy, a citizen of the Republic of France, residing at Saint-Mande (Seine), France, have invented a new, original, and ornamental Design for a Combined Bottle and Holder Therefor, of which the following is a specification, reference being had to the accompanying drawing, forming part thereof.

In the drawing:

Fig. 1 is a top perspective view of a combined bottle and holder therefor, showing my new design;

Fig. 2 is a bottom perspective view thereof;

Fig. 3 is a side elevational view thereof; and

Fig. 4 is a top perspective view thereof, showing the holder portion removed from the bottle portion thereof.

I claim:

The ornamental design for a combined bottle and holder therefor, substantially as shown.

LOUIS LEON DUJONCQUOY.
